JARED H. PLAISTED, OF MELROSE, MASSACHUSETTS.

NON-REFILLABLE BOTTLE.

1,081,553.

Specification of Letters Patent. Patented Dec. 16, 1913.

Application filed January 17, 1911, Serial No. 603,132. Renewed May 31, 1913. Serial No. 771,084.

To all whom it may concern:

Be it known that I, JARED H. PLAISTED, of Melrose, in the county of Middlesex and State of Massachusetts, have invented certain new and useful Improvements in Non-Refillable Bottles, of which the following is a specification.

This invention has for its object to provide a simple, durable, efficient and relatively inexpensive anti-refilling attachment 10 adapted to be applied to a bottle neck of ordinary shape and to be constructed of a material or materials such as glass, the use of which is not objectionable in devices for 15 this purpose.

The invention consists in the improvements which I will now proceed to describe and claim.

Of the accompanying drawings which 20 form a part of this specification,—Figure 1 represents an end view of an attachment embodying my invention; Fig. 2 represents a side elevation of the same, Figs. 1 and 2 showing the preferred size of the attachment; Fig. 3 represents an enlarged section on line 3—3 of Fig. 2 showing the attachment in place in a bottle neck; Fig. 4 represents a section on line 4—4 of Fig. 3; Fig. 5 represents a view similar to Fig. 3 showing the bottle neck inverted for pouring; and Figs. 6 and 7 represents views similar to Fig. 3 showing the bottle neck held horizontally as it would be in attempting to refill the bottle.

Similar reference characters indicate the same or similar parts in all the figures.

In the drawings, 12 represents a plug formed to be inserted in a bottle neck 13, the periphery of the plug being preferably 40 tapered or frusto-conical, and the interior of the bottle neck being correspondingly formed to have a close fit on the periphery of the plug. The plug may be immovably secured in the bottle neck by any suitable 45 means such as a cement composed of soluble glass, although if desired, other means may be employed for securing the plug in place and preventing its removal.

In the inner end portion of the plug is 50 formed a valve chamber 14, having a flat annular bottom 15, which surrounds a passage 16 communicating with the interior of the bottle. The circular wall 14^a of the valve chamber intersects the valve seat 15 and its outer portion is curved or inclined

at 14^b, said portion overhanging the valve seat 15 and merging into the concave or dome shaped top 14^c of the chamber.

The portion 14^a of the circular wall of the valve chamber is inclined outwardly to the 60 curved portion 14^b, said portion 14^a having therefore a gradually increasing diameter from the valve seat outwardly to cause the valve hereinafter described to drop slightly when it is displaced outwardly, and thus 65 assume an eccentric position when the bottle is held in an approximately horizontal position. In other words, when the valve is displaced outwardly it drops edgewise so that only its lower edge portion bears on the wall 70 of the valve chamber, its upper edge portion being separated from said wall.

In the periphery of the plug are formed a series of longitudinal ducts 17 which extend through the outer end of the plug. The 75 outer portions 17^a of the bottoms of said ducts are preferably parallel with the periphery of the plug so that the outer portions of the ducts are of substantially uniform depth from their outer ends part way 80 to their inner ends. The inner portions 17^b of the bottoms of the ducts are inclined inwardly and intersect the outer part of the curved portion 14^b of the valve chamber wall, the object of the inclination of the portions 85 17^b being to guide liquid inwardly against the periphery and outer side of the valve, as hereinafter described. The sides of the ducts 17 are extended inwardly beyond the inclined bottom portions 17^b and terminate 90 in abutments 17^c which are located above the valve seat. The extended portions of the sides of the ducts, the abutments 17^c, and the inner ends of the inclined bottom portions 17^b form margins of inclined ports 17^d which 95 are caused by the curved portion 14^b of the valve chamber wall to overhang the valve seat.

18 represents the valve, which is a relatively thin disk having substantially flat 100 sides, the inner side of the valve being adapted to close on the seat 15 and form a liquid tight joint therewith. The diameter of the valve is substantially equal to that of the valve seat, so that when the valve is seated, it substantially fills the lower portion of the outwardly inclined wall 14^a, and its thickness is such that when the valve is displaced from the seat, its outer side abuts against the curved portion 14^b of the valve 110

chamber wall, and is arrested thereby with its outer side separated from the top 14° and from the outer ends of the ports 17^a , the inner side of the valve being at the same time 5 separated from the inner ends of said ports formed by the abutments 17^c .

It will now be seen that when the bottle is inverted, as shown by Fig. 5, liquid is permitted to flow outwardly from the inner portions 10 of the ports 17^a across the periphery of the valve and through the ducts 17. It will also be seen that when the bottle is held in an approximately horizontal position and fluid under pressure, either liquid 15 or air, is forced inwardly through the ducts, such fluid will impinge on the periphery and the outer side of the valve and will be deflected inwardly toward the center of the outer side, thus exerting pressure which 20 promptly closes the valve.

When the bottle is held horizontally the valve naturally assumes an inclined position, as shown by Figs. 6 and 7. Whether the inclination be in one direction, as shown 25 by Fig. 6, or in the opposite direction, as shown by Fig. 7, fluid pressure through all the ducts will be exerted on the outer side of the valve and will force it to its seat as indicated by dotted lines in Fig. 6.

30 The abutments 17^c at the inner ends of the ducts are adapted to arrest a tampering instrument such as a wire employed in an effort to beat the device, such instrument being guided by the outer portion of the 35 duct, (made of uniform depth as above stated) against the abutment. In case the tampering instrument enters the valve chamber through the upper duct (the bottle being held horizontally) it will pass between the 40 upper edge of the then eccentrically located valve and the wall of the valve chamber and abut ineffectively against the valve seat. A tampering instrument inserted through the lower duct will of course abut against the 45 outer side of the valve and simply force it against the seat. The ducts are preferably of zig-zag form, as shown by Fig. 2, to increase the difficulty of inserting a tampering instrument.

50 The combined cross sectional area of the ducts is such that they will collectively carry off, without clogging, the quantity of liquid which passes through the passage 16 surrounded by the valve seat, and will also permit 55 the entrance into the bottle of sufficient air to replace the escaping liquid. The periphery of the valve is preferably rounded or curved, as shown, to reduce the bearing of the valve on the wall of the chamber and 60 minimize frictional resistance to its sliding movement on said wall. The abutments 17^c at the inner ends of the ducts not only serve as above stated to resist inward movement 65 of a tampering instrument, but also to assist in deflecting inwardly any fluid that may be

forced from the outside into the ducts. The zig-zag form of the ducts is not considered indispensable, since the other provisions herein described for frustrating attempts to beat the device would be efficacious if the ducts 70 were straight.

Important structural features distinguishing my invention are the following, first, the disk valve having a continuous circular edge, the diameter of which is substantially 75 equal to the greatest diameter of the valve seat; second, the outward and upward inclination of the circular wall of the chamber from the valve seat outwardly; third, the inward inclination or curvature of the circular wall from the outwardly inclined portion 80 of said wall to the top of said chamber; fourth, the concave or dome shape of said top; and fifth, the ducts 17 formed in the periphery of the plug 12 and extending 85 through the outer end of the plug partly to the inner end; abutments 17^c being formed at the inner ends of the ducts. These features all contribute to the successful operation 90 of the device. The described diameter of the valve and the continuity of its circular edge insures the interposition of said edge between the wall of the passage 16 and the ports 17^a both when the valve is closed and when it is opened. When the valve is 95 closed its margin is between the passage 16 and the inner ends of the ports 17^a , and when the valve is open its margin is between said passage and the outer ends of the ports, so that liquid may flow freely through each 100 of the ports. The inclination of the circular wall of the valve chamber enables the valve to move entirely from its seat when the bottle is in pouring position, so that none of the ports are obstructed by the valves 105 when the latter is open. The curved form of the top of the valve chamber, and the intersection of the inner ends of the ducts with the marginal portion of said concave 110 top insures the formation of a space between the top of the chamber and the outer side of the valve when the latter is open, said space communicating with the outer ends of all the ports so that when liquid is forced 115 inwardly through the ducts, it is caused to impinge against numerous points on the outer side of the valve and close the latter.

I claim:

An anti-refilling attachment for bottles, comprising a plug adapted for insertion in a 120 bottle neck and having a valve seat in its inner end portion surrounding a passage communicating with the interior of the bottle, and a circular valve chamber between said valve seat and the outer end of the plug, a 125 disk valve in said chamber, the wall of the chamber being inclined outwardly from the valve seat partly to the outer end of the chamber and from thence inwardly to form a concave chamber top, whereby the valve 130

will tilt on one edge when the bottle is inclined, said plug being also provided with a series of longitudinal ducts in its periphery extending through the outer end of the 5 plug partly to its inner end, abutments being provided at the inner ends of the ducts to arrest a tampering instrument, the bottoms of said ducts intersecting the concave

top of the valve chamber at points within the wall of said chamber and forming ports. 10

In testimony whereof I have affixed my signature, in presence of two witnesses.

JARED H. PLAISTED.
